UNITED STATES PATENT OFFICE.

MONTAGUE E. PERKINS, OF BRISTOL, CONNECTICUT.

BAG-HOLDER.

SPECIFICATION forming part of Letters Patent No. 609,589, dated August 23, 1898.

Application filed August 12, 1897. Serial No. 648,050. (No model.)

To all whom it may concern:

Be it known that I, MONTAGUE E. PERKINS, a citizen of the United States, residing at Bristol, in the county of Hartford and State of Connecticut, have invented certain new and useful Improvements in Bag-Holders, of which the following is a specification.

My invention relates to improvements in bag-holders; and the main objects of my improvement are simplicity and economy in construction and efficiency and convenience in operation.

In the accompanying drawings, Figure 1 is a front elevation of my bag-holder, the lower part of the standard upon which it is supported being represented as broken away. Fig. 2 is a plan view of the same. Fig. 3 is a side elevation, and Fig. 4 is a detached front elevation, of the supporting-bracket for my bag-holder.

A designates the frame of my bag-holder, the same being substantially a strap or plate like structure bent flatwise on two transverse lines and forming, when said bent plate is seen in edge view, three sides of a right-angled rectangular figure. For convenience I will divide this frame into three parts—the back 5 and sides 6 6, the lower portions of which sides are perforated and act as strips. On the upper edge of the sides I form or secure suitable hinge-lugs 7, to which I pivot the hinge-lugs 8 of the swinging wings 9. The particular manner of forming the hinge-lugs or hinges is immaterial so long as the wings are hinged or pivoted from their upper edge to the sides 6 6. The lower part of each wing is provided with any desired number of upwardly-curved points 10, facing outwardly and extending through holes in the stripper portion of the sides 6 6 when the wings are swung downwardly, as shown. The rear end of each wing is also provided with a lug 11.

Upon the front side of the back 5 of the frame I pivot the lever 12 on the pin or fulcrum 13, and one end of said lever has attached to it or formed thereon a handle 14, that projects to one side of the bag-holder, as shown. This lever is connected with the lugs 11 of the wings 9 by means of links 15, pivoted by one end to said lugs and by their other end to the said lever, as shown. Projecting from the front of the back 5 of the frame A

is a stop 16 for limiting the swinging movement of said wings when moving away from the sides 6 6. I prefer to employ a spring for holding the parts in their normal position. As shown, the spring 17 is formed of wire, with one end hooked over the stop 16, its body extended under the fulcrum 13 of the lever, and its opposite end hooked over the upper edge of the lever 12, as at 18.

The bag-holder thus far described when secured to any suitable support is an operative device; but I prefer to provide the same with a bracket 19 and bracket-plate 20 for adjustably supporting the bag-holder at different heights. The bracket 19 is designed to be secured by its body or middle portion on the rear side of the back 5 of the frame A. Its upper end is bifurcated and provided with two hooks 21, while its lower end, which is turned rearwardly, is provided with a central slot 22, Fig. 4. The bracket-plate 20 is provided with a series of notches 23 at each edge and in its front face with a forwardly-projecting mid-rib 24. The bracket-plate 20 may be secured to a standard 25 or to any other suitable support. I prefer to have the standard or support to which the bracket-plate is secured of less width than the width of the plate between its notches 23, whereby said standard will not be in the way of the hooks 21 of the bracket-plate; but if the standard or support is wider suitable recesses may be cut therein to receive said hooks.

The bag-holder is secured to the bracket-plate 20 by passing the hooks through the notches 23 in said plate, so that the edge of the metal at the lower sides of the recesses 23 may be received within said hooks, as best shown in Fig. 3, while the mid-rib 24 enters the central slot 22 of the bracket, thus securely attaching the bag-holder in position for use. The series of notches in the bracket-plate will enable the holder to be set at any desired height. A bag is then secured by its mouth to the said holder by drawing the same on over the points 10, letting the points pass through the fabric of the bag, said bag being drawn taut on the back and two fixed sides of the frame and left slack at the front and unobstructed side. The bag is then filled in any ordinary manner, the holder being of such form as to leave the mouth of the bag

practically unobstructed. If the bag is accidentally overfilled, the three-sided form of frame, which is an important feature of my invention, permits of the use of a scoop introduced from the front in removing the surplus while the bag is still held by the holder. When all is ready to remove the bag, it is only necessary to depress the lever-handle 14, thereby withdrawing the points from the stripper portion of the frame for releasing the bag. The stop 16 will prevent the right-hand wing and its link from being moved so far as to pass the "dead-center," and consequently the spring will always restore the parts to their normal position. The points being curved substantially concentrically to the axis of the wings, they are withdrawn very easily, while at the same time their upwardly-curved form prevents the bag from accidentally slipping off.

I claim as my invention—

1. In a bag-holder, the frame consisting of a strap or plate like structure bent flatwise on two transverse lines and forming when seen in edge view three sides of a right-angled figure, the sides 6, 6, of which are provided at their upper edge with hinge-lugs and toward their lower edge with the stripper portion, in combination with the swinging wings pivoted to the hinge-lugs of said frame by their upper edge, and carrying at their lower portion curved points that register with the openings

therefor in the stripper portions of said sides, and means for operating said wings, substantially as described.

2. In a bag-holder, the combination of the frame having the back 5 and the two fixed sides 6, 6, the lower portions of which fixed sides serve as strippers, the swinging wings 9 pivoted by their upper edges to the said stripper sides and extending downwardly inside of the said stripper sides, the upwardly-curved and outwardly-projecting points mounted on said wings near their lower edge, and mechanism for swinging said wings to and from 45 said stripper sides to project and withdraw the said points through said sides in a curved path, substantially as described.

3. In a bag-holder, the combination of the bracket 19 having the pair of hooks 21 at its upper edge with a space between said hooks, and the rearwardly-extended and slotted lower end, with the bracket-plate of T form in plan or end view, having its mid-rib adapted to be engaged by the slotted lower end of 55 the said bracket and with the back or cross piece of the said T-shaped bracket-plate having in its opposite edges the series of side notches for receiving the said hooks 21, substantially as described.

MONTAGUE E. PERKINS.
